US00D458030S

(12) **United States Design Patent** (10) Patent No.: **US D458,030 S**
 Blaustein et al. (45) Date of Patent: ** Jun. 4, 2002

(54) **HEAD PORTION OF AN ELECTRIC TOOTHBRUSH**

(75) Inventors: **Lawrence A. Blaustein; John Osher, both of Moreland Hills; John R. Nottingham, Hunting Valley; John W. Spirk, Gate Mills, all of OH (US)**

(73) Assignee: **The Procter & Gamble Company, Cincinnati, OH (US)**

(**) Term: **14 Years**

(21) Appl. No.: **29/152,898**

(22) Filed: **Jan. 4, 2002**

(57) **CLAIM**

The ornamental design for a head portion of an electric toothbrush, as shown and described.

DESCRIPTION

FIG. 1 is an enlarged, perspective view of a head portion of an electric toothbrush showing our new design; and, FIG. 2 is a top view thereof.

The dashed lines shown in the figures represent environmental subject matter and form no part of the claimed design. The dotted lines shown in the figures represent the border between claimed subject matter and unclaimed subject matter and form no part of the claimed design.
